UNITED STATES PATENT OFFICE.

THEODORE H. BRISON, OF SIOUX FALLS, SOUTH DAKOTA.

REVERSIBLE RAIN-WATER CUT-OFF.

1,349,808.

Specification of Letters Patent.

Patented Aug. 17, 1920.

Application filed October 24, 1919. Serial No. 333,037.

To all whom it may concern:

Be it known that I, THEODORE H. BRISON, a citizen of the United States, residing at Sioux Falls, in the county of Minnehaha and State of South Dakota, have invented 5 certain new and useful Improvements in Reversible Rain-Water Cut-Offs, of which the following is a specification, reference being had to the accompanying drawings.

This invention relates to an improved reversible rain water cut-off, particularly adapted for use in connection with drain pipes leading from the eaves trough, and an object of the invention is to provide a 10 loose slip jointed rain water cut-off, which will do away with the usual water gate located on the inside of the drain pipe, thereby eliminate considerable trouble and expense in the repair and the manipulation of 15 the water gate.

Another object of the invention is to provide a rain water cut-off, which is very efficient, simple and practical in construction, and which may be easily and quickly 20 removed at any time to permit the drain pipe and the cut-off to be easily and quickly cleaned, which is found very often necessary.

A further object of the invention is to 25 provide a rain water cut-off, so constructed as to permit it to be positioned so that it can drain into a suitable cistern or other receptacle, or so positioned as to permit the rain water to waste, it being possible to 30 easily observe at a distance as to which one of the positions the cut-off assumes.

A still further object of the invention is 35 to provide a rain-water cut-off including a strainer adjacent the funnel shaped top of the cut-off member, for straining and clearing the water as it enters the cistern or other receptacle.

While the design and construction at 40 present illustrated and set forth is deemed preferable, it is obvious that as a result of a reduction of the invention to a more practical form for commercial purposes, the invention may be susceptible to changes, and the right to these changes is claimed, provided they are comprehended within the 45 scope of what is claimed.

The invention comprises further features and combination of parts, as will be herein-after set forth, shown in the drawings and 50 claimed.

In the drawings:

Figure 1 is a view in elevation of the improved cut-off constructed in accordance with the invention, showing the cut-off in a position so as to drain into a cistern. 60

Fig. 2 is a vertical sectional view through the cut-off, showing the cut-off member positioned for guiding the water so that it may waste.

Referring more especially to the drawings, 1 designates the main rain water drain pipe which is clamped to the side of the building by means of a U-clamp 2, which is secured at 3 to the building. Secured by means of a double clamping member 4 to 65 the side of the building is a pair of pipe sections 5 and 6. The pipe section 5 is designed to drain the water, so that it may waste, while the pipe section 6 has a lateral extension 7, through which the water from 70 the main drain pipe may pass into a suitable cistern or other receptacle 8. These pipe sections 5 and 6 are spaced below the main drain as shown. The main drain pipe is aligned axially with the point where the 75 two pipe sections 5 and 6 engage each other.

The rain water cut-off member 9 is in the form of a funnel-shaped body, and its lower portion has an extension 10. This extension 80 is arranged at an angle to the longitudinal center of the funnel-shaped body, so that the extension may, by reversing the funnel-shaped body, engage either one of the pipe sections 5 and 6, so that the rain water may easily and quickly drain, either 85 as waste or into a suitable cistern or other receptacle, for various uses. The funnel-shaped body is partly flattened near its upper portion, therefore it is elongated in cross-section. The upper portion of the 90 funnel-shaped body terminates in a frusto conical part 11 having an enlarged opening 12, which has a slip joint connection with the lower end of the main drain pipe. It 95 will be noted that the funnel shaped body can be easily raised or lowered, for the purpose of connecting and disconnecting the lower extension 10 to and from either one of the pipe sections 5 and 6. Furthermore, the slip joint connection permits the funnel-shaped cut-off body to be reversed, whereby 100 the extension 10 of the cut-off body, when in engagement with either one of the pipe sections 5 and 6, may extend axially with 105 relation to said pipe section. A suitable 110

strainer 13 is arranged in the funnel-shaped cut-off body, at the point where the lower part of the body joins the frusto conical part, thereby providing a wide area, for 5 straining the water as it passes through the cut-off, and also to afford a wide area for the support of the sediment that may be collected.

The funnel-shaped cut-off member may be 10 easily and very quickly removed so as to permit the strainer to be cleaned and to permit the main drain pipe to be swabbed out. Furthermore, the cut-off member may be very easily handled, owing to it being 15 constructed in a single piece, in which case, there is nothing to get out of repair.

Furthermore, this construction of rain water cut-off does away with all complicated parts (which get out of order) here- 20 tofore used, for instance such parts as castings which house the cut-off, also springs, rivets, levers, bearings and turn knobs are eliminated, and furthermore it is unnecessary when using this improved cut-off, to 25 shift the main drain pipe, and furthermore, it is the aim to dispense with the use of water gates inside of the cut-off. By means of the frusto conical top part of the cut-off member, the overflow of the water is pre- 30 vented.

By means of the particular construction of the cut-off member, say for instance, by means of the frusto-conical top, the cut-off member may be disposed so as to connect 35 with pipe sections below, which may be spaced considerably apart. In other words, the cut-off member when being shifted from one pipe section to another disposed below the main drain pipe, the cut-off member is 40 given a partial turn to permit the cylin-

drical end 10 to telescopically enter or telescopically engage the spaced pipe sections below, which may be spaced apart other than shown. The disposition of the cut-off member in this manner is permitted 45 owing to the construction of its upper part and owing to its loose connection with the main drain pipe.

The invention having been set forth, what is claimed as new and useful is:

In a rain water cut off as set forth, the combination with a main drain pipe, of a pair of pipe sections spaced below, one acting to drain waste water, the other acting to drain water to be used, the latter having 55 a lateral extension to drain into a cistern, the main drain pipe being arranged axially between the pipe sections, a cut off member, comprising a main funnel shaped body having its lower end terminating in a cylind- 60 rical extension arranged at an angle to the body, whereby the extension may have a substantial telescopic fitting engagement in either one of said pipe sections, the upper part of the body terminating in a frus- 65 to-conical top portion having an opening of a substantial relatively larger diameter than the main drain pipe, the open end of the frusto-conical top portion having a sub- 70 stantial loose slipping engagement with the lower end of the main drain pipe whereby the body may be raised and lowered a sub- 75 stantially considerable degree, so that the extension may be easily connected and disconnected to and from either one of the pipe sections.

In testimony whereof I hereunto affix my signature.

THEODORE H. BRISON.
